[57] **CLAIM**

The ornamental design for a double roller snap ring, as shown and described.

DESCRIPTION

FIG. 1 is a perspective view of a double roller snap ring, showing my new design;

FIG. 2 is a perspective view in open position;

FIG. 3 is a front view in the closed position;

FIG. 4 is a top view thereof;

FIG. 5 is a bottom view thereof;

FIG. 6 is a right side (gate) view thereof;

FIG. 7 is a left side thereof; and,

FIG. 8 is a rear view thereof.

[63] Continuation of Ser. No. 441,741, Sep. 25, 1989, abandoned, which is a continuation-in-part of Ser. No. 394,070, Aug. 15, 1989, abandoned.
